SERVING TRAY

Thomas H. Simpson, Chicago, Ill., assignor to Munising Wood Products Co., Inc., Chicago, Ill.,
a corporation of Delaware

Application November 5, 1951, Serial No. 17,280

Term of patent 7 years

(Cl. D44—10)

To all whom it may concern:

Be it known that I, Thomas H. Simpson, a citizen of the United States, and a resident of the city of Chicago, county of Cook, State of Illinois, have invented a new, original, and ornamental Design for Serving Tray, of which the following is a specification, reference being had to the accompanying drawing forming a part thereof in which:

The dominant features of my design reside in the handle portion of the tray, shown in full lines.

I claim:

The ornamental design for a serving tray, substantially as shown and described.

THOMAS H. SIMPSON.
